[57] CLAIM

The ornamental design for a combination food container and scoop, as shown and described.

DESCRIPTION

FIG. 1 is a perspective view of a combination food container and scoop showing our new design;

FIG. 2 is a top plan view thereof;

FIG. 3 is a left side elevational view thereof;

FIG. 4 is a front elevational view thereof;

FIG. 5 is a rear elevational view thereof;

FIG. 6 is a right side elevational view thereof;

FIG. 7 is a bottom plan view thereof;

FIG. 8 is a top plan view of a second embodiment of that shown in FIG. 1;

FIG. 9 is a right side elevational view of that shown in FIG. 8;

FIG. 10 is a front elevational view of that shown in FIG. 8;

FIG. 11 is a right side elevational view of a third embodiment of that shown in FIG. 1;

FIG. 12 is a bottom plan view of that shown in FIG. 11; and

FIG. 13 is a front elevational view of that shown in FIG. 11.

FIG. 1.

FIG. 2.

FIG. 3.

FIG. 4.
